UNITED STATES PATENT OFFICE

91,044

DESIGN FOR A SERVICE STATION OR THE LIKE

Charles A. Urbanek, Chicago, Ill.

Application July 24, 1933. Serial No. 48,808

Term of patent 3½ years

To all whom it may concern:

Be it known that I, CHARLES A. URBANEK, a citizen of the United States, residing at Chicago, in the county of Cook and State of Illinois, have invented a new, original, and ornamental Design for a Service Station or the like, of which the following is a specification, reference being had to the accompanying drawings, forming part thereof.

Figure 4 is a horizontal section along the line 4—4 of Figures 1, 2 and 3.

I claim:

The ornamental design for a service station or the like substantially as shown.

In witness whereof, I have affixed my signature.

CHARLES A. URBANEK.
